UNITED STATES PATENT OFFICE.

ARTHUR F. NESBIT, OF WILKINSBURG, PENNSYLVANIA.

DUST COLLECTOR.

Application filed December 2, 1925. Serial No. 72,700.

My invention relates to the centrifugal separation of the components of a fluid stream, and finds practical application in dust collectors for coal houses, blast furnaces, and other such particular uses. The objects in view are simplicity of structure and efficiency, to achieve in large measure the end in view.

In the accompanying drawings Fig. I is a view in vertical section of a dust collector of my invention, designed for service in a coal house, and this embodiment will serve in an exemplary way to illustrate my invention. Fig. II is a sectional view on the same plane 15 of the lower continuation of a chamber whose upper part appears in Fig. I. Fig. III is a view in vertical section, on a plane at right angles to that of Figs. I and II, showing a certain connection of suction- 20 transmitting means.

A stream of air, initially laden with coal dust but ultimately relieved of its load, or substantially so, is caused to advance from inlet 1 to outlet 2. These inlet and outlet 25 passageways are conduits square in cross-section, to which and from which round conduits merge. From inlet passageway 1 the conduit "fans out", that is to say, it narrows in one dimension and widens in the other, 30 so that the stream advances in a broad band, whose greater transverse dimension is (Fig. I) in the line of sight. This broad band narrows again and deepens, as it approaches the outlet passageway 2. Any suitable 35 means may be employed for effecting the flow of the stream through the conduit; preferably the means employed include a suction fan, beyond the outlet 2, and indicated diagrammatically at 9.

40 The conduit which carries the broad, band-like stream is curved on a horizontal axis, parallel to the greater transverse dimension of the conduit; and in this particular instance the conduit is loop-shaped in the 45 longitudinal plane which is the plane of section of Fig. I. The incoming and outgoing branches, 3 and 4, of the loop are vertically disposed and lie in parallelism and closely adjacent, while the bend 5 of the loop is 50 in cross-section substantially semi-annular, arching over the horizontal axis of curvature.

55 The conduit is of undiminished size, from the intake end of the loop to the delivery end, but, intermediate the ends of the loop, and preferably toward the down-stream end

of the semi-annular bend, there is a break; the outer wall 51 on the up-stream side of the break recedes on a widening spiral, and overlaps the edge 52 of the wall on the down-stream side of the break. This edge 52 is remote from the opposite inner wall 53 of the loop at a distance not less than, and preferably equal to, the normal width of the loop, 60 before the recession of the outer wall began. 65 Thus the conduit continues in two branches; the inner branch is, from its spring, of cross-sectional area not less than the normal cross-sectional area of the trunk conduit from which it springs; and both conduits 70 may, as Fig. I of the drawings shows, widen somewhat as overlapped spiral passageways, from the point from which they spring. The inner branch continues in the outgoing lead 4; the outer leads to the dust-collecting 75 chamber 6. This chamber 6 is of relatively greater capacity and of greater cross-sectional area than the main conduit. It is airtight, and, as presently will be more fully explained, a condition of reduced pressure is 80 maintained within it.

The shell of sheet metal which forms the dividing wall between the branching passageways, and whose tip forms the edge 52, may be adjustable in a plane parallel to the axis of curvature of the loop and substantially tangent to the normal outer wall of the loop at the down-stream end of its semi-annular bend. The adjustability may be accomplished by mounting the shell of metal 85 alluded to, on slides 7. These slides may carry racks 71, and suitable rotatable gear wheels 72 may be provided which, engaging the racks, afford means for adjusting the 90 particular position of the edge 52. This minute adjustability gives adaptability of the apparatus to varying conditions in the material under treatment. And it will be perceived that, in consequence of the particular arrangement and the fact that the shifting is in a substantially tangential plane, the 95 adjustment of the position of edge 52 within limits adequate for the ends indicated, effects no appreciable variation in the distance at which the edge 52 lies remote from the inner 100 wall 53 of the loop.

Similarly as one branch is formed, a plurality of branches may be formed, leading from the bend of the loop. Fig. I shows two branches. The second sheet metal shell, 110 which terminates in a second edge 54, has all the characteristics of the first, and is simi-

larly mounted for adjustment. In this case there are two outer, dust-carrying passageways, and, while a different particular arrangement may if desired be adopted, both 5 branches are here shown to discharge into a common dust-collecting chamber 6.

Any preferred particular means may be employed, for collecting and removing the dust which accumulates in chamber 6. Fig. 10 I of the drawings bears indication that the wide chamber 6 narrows downwardly to a delivery leg, and Fig. II shows the delivery leg 61 to be provided with a double delivery, in the form of two bells 62.

15 The plurality of delivery bells is a matter which implies a condition of pressure inequality, and directs attention to the means provided for maintaining within chamber 6 a condition of reduced pressure, to the end 20 that the flow from loop 5 through the break in the outer wall and through the branch which widens thence and delivers to chamber 6, shall be smooth, and free of retardations and eddies. Across the depth of 25 chamber 6 extends a nozzle 8. The passageway 81 from this nozzle opens to a box 82. Within the box (see Fig. III) partitions 83 subdivide the space. An eduction pipe 84 leads from the box, and means are provided 30 for creating a condition of suction within the eduction pipe. The provision of the partitions 83 affords better distribution of the suction condition throughout the length of nozzle 8, that is to say, throughout the 35 depth of chamber 6. The fact that chamber 6 is of relatively great capacity brings it about that the dust settles to the bottom, while flow through the nozzle 8 is an easy flow of relatively clean air.

40 Operation is as follows: A stream flowing from 1 to 2 is spread to flow in a wide shallow band, and the band is curved on an axis parallel with its width. The curved stream takes the form of a barrel vault, 45 arched above a horizontally extending axis. As the stream advances through loop 5 its burden of coal dust (or burden of other separable and relatively heavy material) will by centrifugal action tend to segregate, 50 and advance in a layer against the outer wall of the curve. When the break in the continuity of the conduit walls is reached, this outer heavier layer flows easily along the widening spiral 51 to which it clings, while 55 the edge 52 shears it from the main body of the stream. The main body of the stream, so unburdened, flows on to the outlet 2. The segregated stream of coal dust (air-born, of course) discharges into chamber 6. The 60 condition of reduced pressure within chamber 6 has ensured free and easy down-draft discharge. The chamber 6 is large; within it the stream is arrested; the coal dust gravitates to discharge leg 61; while the unburdened air is sucked out through nozzle 8.

This eduction conduit 84 may be led to passageway 1, and in that case the single fan 9 situated beyond 2 will maintain the conditions described. This particular arrangement is indicated in Fig. I. A separate fan or equivalent means might manifestly be employed for creating suction within conduit 84.

Adjustment of edge 52 effects the cutting away of a deeper or shallower layer of coal 75 dust.

I claim as my invention:

1. Means for effecting centrifugal segregation and separation of the components of a flowing stream which include a main conduit of undiminished cross-sectional area from its inlet to its outlet end, included between opposite parallel walls and curved on an axis to which such opposite walls are parallel, the walls of the conduit through- 80 out the extent of the curve being (but for the opening to the branch conduit) continuous, a branch conduit opening through the wall of the main conduit on the outer side of the curve, such branch conduit being of 85 increasing cross-sectional area and being curved in a widening spiral about the same axis, and means for causing fluid to stream through the conduit and the branch conduit.

2. Means for effecting centrifugal segregation and separation of the components of a flowing stream which include a main conduit of undiminished cross-sectional area from its inlet to its outlet end, included between opposite parallel walls and curved on an axis to which such opposite walls are parallel, the walls of the conduit throughout the extent of the curve being (but for the opening to the branch conduits) continuous, a plurality of branch conduits opening through the wall of the main conduit on the outer side of the curve, such branch conduits branching in immediate succession from the main conduit, the said branch conduits being of increasing 100 cross-sectional area and being curved in widening spirals about the same axis, and means for maintaining at the delivery ends of the main and branch conduits conditions of reduced pressure relatively to that at the intake end of the main conduit.

3. Means for effecting centrifugal segregation and separation of the components of a flowing stream which consist in a curved conduit, in the outer wall of which a break is formed, the outer wall of the conduit from the up-stream side of the break being continued in a spiral of increasing radius and overlapping the wall part at the down-stream edge of the break, the wall part on the down-stream edge of the break being adjustable in a direction tangential to wall curvature, and means for effecting stream flow.

4. Means for effecting centrifugal segre-

gation and separation of the components of a flowing stream which include a main conduit of undiminished cross-sectional area from its inlet to its outlet end, included between opposite parallel walls and curved on an axis to which such opposite walls are parallel; the walls of the conduit throughout the extent of the curve being (but for the opening to the branch conduit) continuous, 5 a branch conduit opening through the wall of the main conduit on the outer side of the curve such branch conduit increasing in width between walls parallel with the said

opposite walls of the main conduit, a dust-collecting chamber of greater cross-sectional area than the main conduit, to which said branch conduit opens, means for maintaining at the delivery end of the main conduit and within said dust-collecting chamber conditions of reduced pressure relatively 15 to that at the intake end of the main conduit.

10 In testimony whereof I have hereunto set my hand.

ARTHUR F. NESBIT.
